UNITED STATES PATENT OFFICE.

EDWIN H. JOHNSON, OF SAYRE, PENNSYLVANIA.

OBSERVATION-TUBE.

1,184,855.

Specification of Letters Patent. Patented May 30, 1916.

Application filed March 4, 1914. Serial No. 822,389.

To all whom it may concern:

Be it known that I, EDWIN H. JOHNSON, citizen of the United States, residing at Sayre, in the county of Bradford and State 5 of Pennsylvania, have invented certain new and useful Improvements in Observation-Tubes, of which the following is a specification.

This invention relates to what might be 10 termed a "sight or look-out tube" for use upon street railway cars, locomotives, motor vehicles, etc., the object thereof being to provide an improved device of this nature which may be manufactured at small cost, 15 may be readily attached to a car vestibule or locomotive cab, and which will operate efficiently to prevent sight openings from becoming obscured or non-transparent by the accumulation of frost, ice, snow, rain or 20 vapors thereon, the invention consisting in the construction, combination and arrangement of parts hereinafter described and claimed.

In describing my invention in detail reference will be had to the accompanying drawings wherein like characters denote like or corresponding parts throughout the several views, and in which:—

Figure 1 is a side elevation of a portion of 30 a street railway car illustrating the attachment in longitudinal section; Fig. 2 is a rear elevation of the attachment as illustrated in Fig. 1; Fig. 3 is a front elevation of the device; Fig. 4 is an enlarged fragmentary sectional view illustrating the manner in which the attachment is supported in its various adjusted positions; Fig. 5 is a rear end view of a portion of a locomotive cab illustrating the arrangement of a 35 modified form of lookout tube thereupon; Fig. 6 is an enlarged longitudinal sectional view of the said modified form of tube, partly in elevation; and Fig. 7 is an enlarged longitudinal section of a pipe joint 40 necessary to operation of the said modified device.

Before proceeding with the description of the drawings, I desire to call particular attention to the fact that while I have

evolved my invention with reference to its 50 use as an attachment for street railway cars, locomotives, and motor vehicles, the same may be readily utilized as a sight tube or opening in connection with rolling stock generally.

Referring now to the drawings by numerals, 1 designates the car in connection with which the attachment is used, the said attachment in its preferred embodiment comprising what might be termed a cone or body 2, the converged end of which extends, tubular in form, as indicated at 3, between the uprights 4 of the vestibule of the car 1 at a point adjacent and above the controller 5. Across the top of the cone 2, at its forward end, is a hood 6, the said hood extending at an angle to the cone whereby to form a protecting element against driving snow or rain during forward movement of the car.

A substantially rectangular frame 7 is 70 mounted in any suitable manner upon the inner end of the tubular extension 3, the said frame having a circular sight opening formed therein, said opening being closed by a glass panel or pane 8 of a size corresponding to the circumference of the tubular extension 3. The panel 8 and cone 2 are thereby made, in the adjustment of the latter, to move in unison.

As a means whereby the glass 8 may be 80 conditioned or heated to prevent the accumulation of frost, moisture, sleet or other sight impeding elements, I provide a heater 9 in the nature of a coiled wire strand arranged to embrace the glass 8, said heater 85 being supported in any suitable manner, preferably by an annular flange 10 extending inwardly from the frame 7 as illustrated to advantage in Fig. 1 of the drawings. At each side of the frame 7, and as a support 90 therefor, I provide a plate 11, the top edges of which are cut at an inclination to form a support for a cover 12 extending inwardly from the front of the car vestibule to overhang the opening in the frame. A second 95 heater 13 is arranged beneath the cone 2 and supported therebeneath through the medium of an extension 14 of the cone, the

said heater being of the electric type, as is also the heater 9, both being connected by suitable conductors 15 with the circuit necessary to the operation of the car 1 in connection with which the device as at present constructed is used.

Ears or lateral extensions 16 are provided, one upon each side of the extension 3, preferably at diametrically opposite points, the 10 said extensions fitting elongated openings or slots 17 within the respective sides of the uprights 4 of the car vestibule, the said slots providing a guide for the attachment in an adjusting operation, as well as a means 15 whereby the said attachment may be supported in the desired adjusted position. Thumb screws 18 are carried by the said extension 16, the thumb screw of each extension operating within slots 19 extending 20 parallel with the slots 17 aforesaid, this arrangement as indicated in Fig. 4 providing for the locking or fastening of the tube or attachment in its properly adjusted position.

Referring now to the modification illustrated in Figs. 5 to 7 inclusive; 1' designates the cab of an ordinary locomotive, 2' the boiler and 3' the window usually positioned at one side of the boiler and within the cab. It is to provide for a clear lookout when the 25 windows 3' are covered with either frost or snow that the present modification is designed, and for this reason an opening 4' is formed within the cab, preferably between the windows 3' thereof. The tube of the 30 modified device is of substantially the same size and shape as the tube of the preferred form, said tube comprising a cone or body 5' having a cylindrical extension 6' upon its inner end, said extension being arranged 35 to fit said opening 4', the diverged end of the cone extending forwardly of the locomotive cab as illustrated to advantage in Fig. 6 of the drawings. The inner end of the cone is annularly grooved as at 7' to 40 provide for the support of a glass panel or pane 8' within the extension 6' through which the engineer may look to obtain a clear view of the roadway or track over which the locomotive is traveling. Said 45 tube 5' is partially closed at its forward end by a hood 9', the purpose of which is obvious. To maintain the pane or panel 8' at a temperature sufficiently high whereby to prevent the accumulation of frost thereon, 50 I provide a heater 10', annular in form, and disposed to encircle the said glass upon the interior thereof, said heater being connected to the boiler 2' through the medium of a pipe 11'. If desired, the heater 10' may 55 be swung to one side of the frame within which the windows 3' are positioned or into the position indicated by the dotted lines in Fig. 5, such movement of the heater being

made possible by a joint connecting the pipe 11' with a second pipe 12', the latter extending into the interior of the boiler. An elbow pipe section 13' is threaded over one end of the pipe 11', the opposite end of the section 13' fitting a band or collar 14' flanged at one end as indicated at 15'. A 65 pipe section 16' enlarged as at 17' is embraced by the collar or band 14', the enlargement 17' abutting the elbow 13' aforesaid. A second elbow pipe section 18' connects the pipe 12' with the pipe section 16', from 70 which arrangement it is apparent that the pipe 11' carrying the heater 10' may be swung with the elbow 13' and collar 14' at an angle to its normal position, this being made possible by the section 16' and the 75 novel or peculiar arrangement of the collar or band 14' thereover. Another pipe 19' in communication with the boiler interior supports a second heater 20', the latter extending into a compartment 21', formed upon the under side of the protector 5' to provide for the heating of the said protector or cone whereby to prevent the accumulation of snow and frost therein. A valve 22' may be provided to control the steam supply 80 to the compartment 21' through the pipe 19' leading thereinto.

From the above arrangement of parts, taken in connection with the accompanying drawings, it will be noted that the heaters 9, 13 and 20' by reason of their disposition beneath the cone or body of the device will condition the latter to cause the snow and sleet accumulating therein to melt and flow therefrom; that the heaters 9 and 10' will 90 prevent the accumulation of moisture, frost or the like upon the glass or panel of the lock out tube; and that by hinging as indicated at 20, the frame 7 of the device, the latter may be opened and closed with respect to the extension 3 to facilitate cleaning of the glass 8 when soiled.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

1. An observation tube comprising a body having its lower wall slanting downwardly 125 toward the outer end thereof, a carrying

structure associated with said slanting wall, and a heating agent carried by said structure in proximity to said slanting wall.

5. 2. The combination with an adjustably mounted observation tube, having its lower wall slanting downwardly to the outer end thereof and having a window associated with the inner end thereof, of a carrying structure secured to the under face of said

slanting wall, and a heating agent arranged 10 in said carrying structure to heat said slanting wall, as and for the purpose specified.

In testimony whereof I affix my signature in presence of two witnesses.

EDWIN H. JOHNSON.
